UNITED STATES PATENT OFFICE.

VERNON ROSS AND ERRETT S. RHOADS, OF KANSAS CITY, MISSOURI, ASSIGNEES TO ROSS RHOADS COMPANY, OF KANSAS CITY, MISSOURI, A CORPORATION OF MISSOURI.

STORE-FRONT CONSTRUCTION.

Application filed July 26, 1920. Serial No. 399,059.

To all whom it may concern:

Be it known that we, VERNON Ross and ERRETT S. RHOADS, citizens of the United States, and residents of Kansas City, in the county of Jackson, State of Missouri, have invented a certain new and useful Improvement in Store-Front Construction, of which the following is a complete specification.

The present invention relates to store front construction, and aims to provide an improved glass securing means particularly adapted for the proper retention of window lights of the heavy plate glass type ordinarily employed in store front window casings.

Accordingly, we have sought to provide an improvement over the type of store front which utilizes a resilient pressure upon the window glass for securing the same in position, and have devised a clamping scheme which exerts an unyielding pressure upon the glass and serves to retain the same in place in a more positive manner.

It is also an object of the invention to provide a clamping or glass securing means of this character which will afford the proper range of adjustment for accommodating different thicknesses of window glass, and will also be of such simple arrangement and construction as to require only unskilled labor for manipulating and installing the same.

It is further sought to devise a glass securing or clamping means which will have no fastening or clamping devices which are exposed to view, for which purpose we have devised an exterior moulding or finishing strip which is so constructed as to be secured by a simple resilient or frictional retaining engagement with the other parts of the construction. In this connection, it is proposed to employ moulding or finishing strips which will exert no pressure upon the glass, either directly or indirectly, in contrast to prior constructions in which said moulding or finishing strips usually constitute a factor in the glass clamping or retaining means.

With the foregoing general objects in view, the invention will now be described by reference to the accompanying drawing illustrating one form of construction which we have devised for embodying the proposed

improvements, after which the novel features therein will be particularly set forth and claimed.

In the drawing—

Figure 1 is a broken plan view, in irregular sections, illustrating a portion of a store front construction embodying the present improvements;

Figures 2 and 3 are sectional views representing sections taken on the lines 2—2 and 3—3, respectively, of Figure 1; and

Figure 4 is a sectional perspective view illustrating a portion of the window casing with the sheathing strip which lines the glass clamping face, and glass supporting ledge of said casing.

Referring now to the drawing in detail, this illustrates the proposed features of improvement in relation to a window casing structure, indicated generally by the reference numeral 5, the said casing being formed with the usual glass clamping face 6 and glass supporting ledge 7. The detail views shown on the drawing may, of course, represent any section of the window casing 5, along either an upright or a horizontal portion of the casing. For providing a suitable sheathing for the clamping face 6 and supporting ledge 7, we provide an angular sheathing strip of such form as to provide a clamping face portion 8 overlying the clamping face 6 of the casing, and a base or anchoring portion 9 overlying the ledge 7, as clearly illustrated in Figures 2, 3 and 4; the face portion 8 of said strip being formed with a rearwardly extending margin 10 provided with an offset 12 for engagement with a longitudinal recess 14 in the casing 5, for aiding in securing the sheathing strip in place, as well as improving the smooth finish of the construction.

The window glass 15 is supported upon a series of suitable blocks 16 located at appropriate intervals along the upper face of the base or anchoring portion 9 of the sheathing strip, and at corresponding intervals between the said blocks 16, the base portion 10 of the sheathing strip is formed with an anchoring rib 17 so stamped as to extend at an angle to the plane of the face 6 of the window casing, as shown in Figure 1. For each of the anchoring ribs 17, a comparatively rigid clamping piece 18 is provided,

- each piece 18 being formed with an inwardly projecting glass engaging portion 19 (see Figure 2), and also with an inwardly projecting cam edge 20 adapted for adjustable 5 clamping engagement with the rib 17 (see Figure 1). Suitable spacing plates or strips 21 formed integral with or separate from clamping portion 8, are interposed at intervals between the glass 15 and said clamping 10 portion 8 of the sheathing strip, and for securing each of the clamping pieces 18 to the window casing, a fastening device, such as a screw 22, is passed through the body portion of the piece 18 and through 15 a slot 23 in the clamping face portion 8 of the sheathing, said slot 23 being of a length approximately equal to that of the rib 17, this being for the purpose of allowing adjustment of clamping piece 18 along its corresponding rib 17 for accommodating different thicknesses of glass 15, the slot 23 enabling the screw 22 to be secured to the clamping face 6 of the window casing at any point opposite the rib 17. 20
- 25 The free end of each clamping piece 18 projects a slight distance beyond its glass engaging portion 19 for affording a retaining finger 24 extending in spaced relation to the outer face of the glass 15 and permitting 30 retaining engagement with one of the flanges 25 of a moulding or finishing strip 26 which is stamped from suitable sheet material adapted to impart a certain degree of resiliency to the edges of the moulding strip. 35 The other marginal flange 27 of said strip 26 is turned inwardly and adapted to be snapped into retaining engagement with the outer marginal bead 28 formed upon the free edge of the base or anchoring portion 40 9 of the sheathing strip; for facilitating engagement of the said flange 27 and bead 28, the width of the base or anchoring portion 9 of the sheathing strip is such as to permit the outer portion thereof to be 45 sprung upwardly, as indicated in Figures 2 and 3, for the purpose of inserting the flange 27 beneath the bead 28 and into retaining engagement therewith.
- Suitable notches 30 are formed in the 50 marginal portion of the base or anchoring portion 9 of the sheathing sheet, while a series of outlet openings 31 are provided in the moulding or finishing strip 26 opposite to the notches 30, to afford the necessary drainage and provide for air circulation, as is customary in constructions of this character. 55
- It will thus be apparent that we have devised a compact and extremely simple construction for fulfilling the desired object of the invention. The series of clamping pieces 60 18 exert a comparatively rigid clamping pressure upon the glass 15, and the provision of the cam portion 20 in conjunction with the anchoring rib 17 and the slots 23

in the sheathing strip, enables the clamping means to be adjusted for varying thicknesses of glass 15 and the parts secured together at any point along the rib 17 and the corresponding slot 23. No separate fastening devices are required for the attachment of the moulding or finishing strip 26, since this is applied by simply hooking its flange 25 over the retaining fingers 24 of the clamping pieces 18, and then snapping its other flange portion 27 beneath the bead 28 of the sheathing strip, and when the said moulding or finishing strip is in place, there are no fastening or clamping devices whatever exposed to view. Thus a very smooth, neat and attractive exterior appearance is obtained by means of the described construction and it will be understood that the moulding or finishing strip 26 is made use of only for the purpose of enclosing the other parts and obtaining the required finished appearance and is not utilized in any way as one of the elements of the clamping mechanism, the glass 15 being wholly supported and held in place by the other parts of the construction. It will furthermore be seen that there are no complicated parts in the construction, the operation of fitting or assembling the parts together and securing the clamping members in position being so simple as to require only unskilled workmen to properly install the construction complete.

While we have illustrated and described what now is deemed to constitute the preferred form of construction, we desire to reserve the right to make such changes or modifications as may fairly fall within the scope of the following claims:

We claim:

1. A store front construction comprising a window casing formed with a ledge and a clamping face, a fixed anchoring rib on the ledge, extending at an angle to said clamping face, a moulding strip fitting against the ledge with one edge in proximity to the outer face of the glass, and a clamping element engaging the rib and the outer face of the glass to hold the latter unyieldingly against movement with respect to said clamping face of the casing; said clamping element engaging and cooperating with the said rib for glass clamping purposes.

2. A store front construction comprising a window casing formed with a glass supporting ledge and a clamping face adjoining said ledge, a sheathing strip overlying said clamping face and provided with a slot, a fixed anchoring rib extending along said ledge adjacent to said slot and at an angle to said clamping face, and a clamping element provided with a fastening device operating through said slot to secure said element to the clamping face, said clamping element being provided with a cam edge co-

operating adjustably with said anchoring rib or glass clamping purposes.

3. A store front construction comprising a window casing formed with a glass supporting ledge and a clamping face adjoining said ledge, a sheathing strip overlying said clamping face and ledge and provided with a slot along said face and also with an extension overlying said ledge, the extension 10 of said strip being formed with an anchoring rib extending at an angle to the clamping face adjacent to said slot, and a clamping element secured to said clamping face through said slot and provided with a cam 15 edge cooperating adjustably with said anchoring rib for glass clamping purposes.
4. In a store front construction, a sheet metal sheathing for the casing of the window, an element secured to the casing and 20 in contact with the window glass for firmly clamping such glass in place, and a moulding strip covering said element and having

a resilient flange retained by said element in proximity to the glass; the opposite edge of the moulding strip and the outer edge of the 25 sheathing being interlocked together with a resilient relation.

5. A store front construction comprising a window casing formed with a glass supporting ledge and a clamping face adjoining 30 said ledge, a sheathing strip overlying said ledge, clamping devices in contact with the window glass and operative to clamp such glass against movement with respect to said clamping face, and a moulding or finishing 35 strip provided with marginal resilient flanges adapted for detachable retaining engagement with said clamping devices and with the outer edge of said sheathing strip.

In witness whereof, we hereto affix our 40 signatures.

VERNON ROSS.
ERRETT S. RHOADS.
